United States Patent Office.

JOHN R. WASHBURN, OF WEST STAFFORD, CONNECTICUT.

Letters Patent No. 82,571, dated September 29, 1868.

IMPROVED LATHE-CHUCK.

The Schedule referred to in these Letters Patent and making part of the same.

TO ALL WHOM IT MAY CONCERN:

Be it known that I, JOHN R. WASHBURN, of West Stafford, in the county of Tolland, and State of Connecticut, have invented a new and improved Lathe-Chuck; and I do hereby declare that the following is a full, clear, and exact description thereof, which will enable others skilled in the art to make and use the same, reference being had to the accompanying drawing, forming a part of this specification.

Figure 1 represents a front view of my improved chuck, with the front plate removed.

Figure 2 is a central vertical section of the same.

Figure 3 is a detail side view of the operating-key.

Similar letters of reference indicate corresponding parts.

This invention relates to a new device for adjusting and operating the jaws of that class of chucks which are provided with gear and scroll-wheels, and the invention consists in attaching the operating-pinion to the key, so that it will form part of the key, and not of the chuck, as usual.

Thereby the necessity of providing bearings for the pinion is overcome, and the application of the key to any side of the chuck is rendered possible by providing a series of apertures, for the insertion of the key, through the sides of the chuck.

A, in the drawing, represents the case or shell of the chuck. The same is made either of one piece or of two, as may be desired, it not being absolutely necessary to make it of two pieces, as there are no bearings for the pinion to be provided in its sides.

The front plate *a* of the case is slotted to admit the jaws *B*, as usual.

C is a bevel or other gear-wheel, mounted on the tubular axle of the case *A*, within said case.

The front face of the wheel *C* is provided with a scroll-track for operating the jaws, as shown in fig. 2, and as found in many existing chucks.

By turning the wheel *C*, the jaws will be set as far apart as may be desired.

D is the key for turning the wheel *C*. On the end of this key is firmly secured a bevel or other pinion *b*, as is clearly shown in fig. 3.

In the sides of the case *A* is a series of apertures *c c*, fig. 1, through either of which the key may be inserted. The projecting end of the axle *d* of the pinion fits into one of a series of sockets *e e*, provided in the tubular axle of the case *A*, respectively opposite the apertures *c*, as is more clearly shown in fig. 1.

When the key has in this manner been inserted in the chuck, its pinion *b* meshes into the teeth of the gear-wheel *C*, and by then turning the key, the scroll will be turned so as to set the jaws.

It is not absolutely necessary that there should be a series of apertures *c* and sockets *e*; one may be sufficient; but it is convenient to have more, as then the key can be applied in any portion of the chuck.

I do not claim anything in the construction of the chuck, as far as the manner of inserting and operating the jaws is concerned, nor do I claim a pinion for operating the scroll-wheel *C*, nor the key for operating the pinion; but

I do claim, and desire to secure by Letters Patent—

1. The detached key *D*, carrying the bevelled pinion *b*, and adapted to fit into a series of apertures, *e*, formed through the sides of the case *A*, to allow the same pinion and key to be applied at either side of the chuck, whereby the key and pinion serve to operate any number of chucks, as herein shown and described.

2. The key *D*, when provided with a pinion, *b*, attached to its end, in combination with the perforated case *A*, jaws *B*, and scroll-wheel *C* of a lathe-chuck, all made and operating as herein shown and described.
